UNITED STATES PATENT OFFICE.

FRANK IBERT, OF NEW YORK, N. Y.

PIPE-NOZZLE.

SPECIFICATION forming part of Letters Patent No. 653,677, dated July 17, 1900.

Application filed April 10, 1900. Serial No. 12,287. (No model.)

To all whom it may concern:

Be it known that I, FRANK IBERT, a citizen of the United States, and a resident of New York, (Brooklyn,) county of Kings, and State 5 of New York, have invented certain new and useful Improvements in Pipe - Nozzles, of which the following is a specification.

This invention relates to a nozzle for steam-pipes which is so constructed that it will 10 break the force of the steam ejected. To effect this, I arrange within the nozzle a convolute web, which deflects the steam and causes it to assume a spiral course before issuing from the nozzle.

15 In the accompanying drawings, Figure 1 is a longitudinal section of my improved pipe-nozzle, showing it applied for injecting steam into a water-tank. Fig. 2 is an end view of the nozzle, and Fig. 3 a longitudinal section 20 of a modification.

The letter *a* represents the tubular shell of the nozzle, open at both ends and adapted to be coupled to a steam-pipe *b*. Within the shell *a* is contained a spiral web *c*, which forms 25 a convolute passage between its threads. The shell *a* projects at its discharge end *a'* beyond the end of the web and is provided, preferably, with an inclined lateral slot *a''*, arranged substantially in the direction of 30 the convolute thread. As the steam passes through the nozzle it is deflected from a straight or direct into a tortuous course, so that its force is broken, and that it will issue from the nozzle in a gentle stream.

35 The drawings show the nozzle *a* projecting into a tank *A* below the water-level thereof and in which the water is to be heated by the steam, such and similar tanks in the form of steaming-tanks, mash-tubs, cookers, &c., being used by brewers. Heretofore with this 40 class of vessels the steam would frequently issue in so violent a form that the building

would shake and that the different parts of the apparatus would soon work loose. With my invention these objections are overcome 45 and a quiet admixture of the water with the steam without noise or rattling is assured. The lateral slot *a''*, which is submerged, serves to permit some of the steam to escape laterally into the water, so that the body of the 50 steam is subdivided and its force is thus still more broken.

In Figs. 1 and 2 the convolute web is shown to be fixed and to be attached directly to the inner face of the shell *a*. In Fig. 3 it is made 55 rotatable, being provided with a shaft *c'*, hung in radial bearings *d*, that project inwardly from the shell *a*.

Although the invention is shown to be applied to a liquid-tank, I do not wish it to be 60 understood that I limit myself to such use. Thus the invention may be applied to steam-pipes for radiators and, in fact, to any nozzle from which steam issues and within which the force of the jet is to be broken. 65

What I claim is—

1. A pipe-nozzle composed of a tubular shell and a convolute web within said shell, the discharge end of the shell projecting beyond the convolute web and being provided 70 with a lateral discharge-slot, substantially as specified.

2. The combination of a tank with a tubular nozzle opening into the same below the water-line, a convolute web within the nozzle, and a steam-pipe to which the nozzle is coupled, substantially as specified. 75

Signed by me at New York city, county and State of New York, this 9th day of April, 1900.

FRANK IBERT.
